Patented Aug. 9, 1921.

INVENTOR:

Henry Reuhl,

BY John Elias Jones,

ATTORNEY.

UNITED STATES PATENT OFFICE.

HENRY REUHL, OF CINCINNATI, OHIO.

DESIGN FOR A TOY BOWLING-ALLEY.

58,686.

Specification for Design.

Patented Aug. 9, 1921.

Application filed April 22, 1921. Serial No. 463,636. Term of patent 7 years.

To all whom it may concern:

Be it known that I, HENRY REUHL, a citizen of the United States of America, residing at Cincinnati, in the county of Hamilton and State of Ohio, have invented a new, original, and ornamental Design for a Toy Bowling-Alley, of which the following is a specification, reference being had to the accompanying drawing, forming part thereof.

The view shown is a perspective one of the toy bowling-alley embodying my design.

I claim:

The ornamental design for a toy bowling-alley, as shown and described.

HENRY REUHL.
